MARK-OUT CABINET FOR PRESS
MAKE-READY

Harrison S. Ransom, Moline, Ill.

Application August 15, 1932, Serial No. 628,840

8 Claims. (Cl. 240—2)

The present invention relates to apparatus for the use of printers in getting their forms made ready on press for printing. As is well known by those skilled in the art, when a type form is set up and printed from it does not make impressions of the same intensity all over the page. Under such circumstances, it is necessary to determine what parts of the impression need strengthening or reducing so that it will be uniform throughout. This is ordinarily done by examining the imprint at a window where the imprint can be so placed with relation to the window that light coming therethrough will shine across the reverse side of the paper. Often-times, it is inconvenient to carry the printed sheet from the press to the window and sometimes there is no window available through which sufficient light comes to make a success of examining the impression. It is therefore the purpose of my invention to provide means whereby printed sheets may be illuminated evenly and clearly, notwithstanding the absence of any source of external illumination; to provide an inexpensive apparatus for the purpose indicated; to provide an apparatus which is more efficient in operation than what has heretofore been used for the purpose indicated; to provide an apparatus which is more effective irrespective of the illumination of the room in which used; and such further objects, advantages and capabilities as will hereafter appear and as are inherent in the construction disclosed herein. My invention further resides in the combination, construction and arrangements of parts illustrated in the accompanying drawing of the two forms of my invention and I desire the same to be understood as illustrative only and not to be interpreted in a limiting sense.

In the drawing annexed hereto and forming a part hereof,

Fig. 1 is a front elevation illustrating one embodiment of my invention;

Fig. 2 is a transverse section of the structure illustrated in Fig. 1;

Fig. 3 is a transverse section similar to Fig. 2 but illustrating a different embodiment of this invention;

Fig. 4 is a fragmentary sectional elevation illustrating adjustment mechanism utilized in the structure shown in Fig. 3.

This construction will now be described in greater detail in connection with the annexed drawing in which the cabinet of my invention is illustrated as being supported upon any suitable

table 1. While the device is shown as being constructed entirely independently of the table, it will of course be understood that it may be made integral therewith, taking the place of the table top 2. This device is illustrated as comprising a bottom 3, a back 4, a top 5 and ends 6 and 7. The latter are wider at the forward ends than at the back and therefore support the top at an inclination with respect to the bottom. In the structure illustrated in Figs. 1 and 2, the bottom 3 is integral and rigidly connected to the ends 6 and 7, while in the construction shown in Fig. 3, a portion 8 of the bottom is hinged as indicated at 9 to the other part of the bottom for a purpose to be set forth more fully hereinafter.

A shelf 10 may be mounted within the cabinet and above this may be placed a second shelf. Between these shelves is a drawer 12 or a plurality of drawers in which supplies and tools may be kept, if desired. On the under side of the shelf 10 are mounted any suitable number of lamps 13 which may be of any design most appropriate for the work involved. Lamps 14 are mounted in the cabinet, either on the under side of the top 5 or on the ends 6 and 7, their purpose being merely to illuminate the interior of the cabinet more completely than can be done by the lamps 13. Suitable switches 15 and 16 control the supply of current to the lamps 13 and 14 and are by preference located inside of the cabinet.

In the construction illustrated in Figs. 1 and 2, a shield or apron 17 depends from the shelf 10 to shut off the light from the operator's eyes, while permitting illumination of the paper 18 spread out upon the bottom 3. In structures in which the bottom 3 is rigid, as shown in Fig. 2, it is preferred to have the lamps 13 some distance away from the bottom so as to get the proper angle of illumination upon the paper 18. On the other hand, much the same effect can be secured with a lower mounting of the lamps 13 if the bottom or a portion thereof be hinged as shown in Fig. 3 so that it can be raised as shown by dotted lines in this figure. However, with such an arrangement it is desirable to provide a pivoted apron 19 so that this can be adjusted in accordance with the position of the section 8 of the bottom. Adjustability of this apron can be secured in various ways, one of which is illustrated in Fig. 4 in which a shaft 20 is shown as secured to the apron 19 and extending through the end 7 of the cabinet. This shaft is shown as provided with a handle 21 whereby it may be rotated. As illustrated in this figure a socket 22 may be formed in the wall 7 for the reception of the spring 23

which places a pressure upon the apron 19 to hold the same in adjusted position. A washer 24 may be mounted on the shaft 20 between the edge of the apron 19 and the end of the spring 23. The opposite end of the apron may be provided with a short stub shaft extending into or through the end 6 so as to complete the axis on which the apron is turned.

If it be desired to improve the illumination upon the paper, a reflector of any suitable type may be mounted upon the back wall 4, either rigidly or so that it can be adjusted in position. The location of this reflector is indicated at 25 and adjusting means is indicated by the numeral 15 26. These are not to be understood as illustrating detailed construction but as indicating, rather, the locations of such elements.

While the fixed apron 17 has been illustrated in connection with the fixed bottom 3 and the 20 pivoted apron 19 in connection with the pivoted bottom section 8, it is desired that this be understood as merely an attempt to illustrate these features without implying that these parts are to be used in the particular relationships shown, it 25 being possible to use either type of apron with either type of bottom. Likewise, the bottom 10 may be either high or low with either of the forms of the bottom 3. Also, the reflector 25, if used, can be used with any combination of the other 30 elements. Furthermore, it is probable that not so many lights 14 will be used as indicated in Figure 1 as it is not at all likely that that number will be required to amply illuminate the interior 35 of the cabinet when working therein. It is of course preferred to cut off the current from the lamps 14 when relying upon the illumination from the lamps 13.

It is believed that it will be understood from the foregoing that the specific description of 40 structure and method set forth above may be departed from without departing from the spirit of my invention as set forth in this specification and the appended claims.

Having now described my invention, I claim:

45 1. A cabinet of the character indicated having top, bottom, back, and ends which are impervious to light and having its front open, illuminating means adjacent the back and spaced at intervals along same, reflecting means back of the illuminating means to assist in reflecting light forwardly and means in front of the illuminating means to prevent the direct rays of light from the illuminating means from reaching the eyes of the user but which is so placed as to enable the light to 50 shine upon a paper upon the bottom of the cabinet.

60 2. A structure as defined by claim 1 having a hinged bottom which may be turned up at its front edge to vary the angle of illumination upon the printed sheet.

65 3. A structure as defined by claim 1 in which the shield between the illuminating means and the eyes of the user is adjustable to vary the amount of illumination which may reach the outer edge of the printed sheet.

4. A make-ready cabinet closed except on the

front side, illuminating means mounted on the interior of the cabinet for illuminating the interior thereof for the convenience of the operator, other illuminating means adjacent the back portion of the cabinet, means for controlling the illumination of each of said illuminating means, and shielding means positioned in front of said other illuminating means enabling the light from said other illuminating means to shine upon the bottom of the cabinet but preventing such light 10 from shining into the eyes of the person using the cabinet.

5 5. A make-ready cabinet having opaque top, back, and ends for excluding from a paper upon the bottom of the cabinet light from a source 15 external to the cabinet, a shelf mounted there-in adjacent the back of the cabinet, illuminating means depending from the shelf, and an apron mounted adjacent the forward portion of the shelf and normally depending therefrom to 20 prevent light from shining from said illuminating means to the eyes of the person using the cabinet but permitting said light to shine upon a printed sheet in the bottom of the cabinet. 25

6. A cabinet of the character described having opaque top, back and ends and a hinged bottom, and illuminating means mounted adjacent the back so as to illuminate the bottom, and shielding means depending in front of the illuminating means for preventing the light from the illuminating means from shining directly into the eyes of the person using the cabinet but interfering in no way to prevent the light from shining upon a paper mounted upon the hinged 35 bottom. 30

7. A make-ready cabinet having non-transparent top and ends and an open front, illuminating means in the back portion for illuminating a printed sheet supported in the bottom of the 40 cabinet, and shielding means depending toward the bottom of the cabinet in front of the illuminating means and extending across the cabinet, said shielding means being mounted independently of the illuminating means at a point 45 remote from the front of the cabinet and shutting off the light from shining directly into the eyes of the person using the cabinet, but not keeping the light from shining on a printed sheet placed upon the bottom of the cabinet. 50

8. A make-ready cabinet having closed top, back and ends and an open front, illuminating means in the back portion for illuminating a printed sheet supported in the bottom of the cabinet, and shielding means depending toward the bottom of the cabinet and extending across the same in front of the illuminating means, said shielding means shutting off the light from shining directly into the eyes of the person using the cabinet but keeping the light from shining on a printed sheet placed upon the bottom of the cabinet, said shielding means having a pivotal mounting whereby the user of the cabinet is enabled to secure adjustment of the spread of illumination over the surface of the printed sheet. 65
